VISE

Walter Haas, Basel, Switzerland, assignor of
one-half to Elektrizitäts-Aktiengesellschaft
Wädenswil, Zurich, Switzerland

Application January 11, 1943, Serial No. 472,067
In Switzerland December 12, 1941

4 Claims. (Cl. 81—38)

The object of the present invention is a range reducing insertion vise provided with a supporting plate having a bearing surface for the work-piece, wherein two gripping jaws for holding the same are relatively movable toward and from each other. The main feature of the invention resides in the fact, that the two said gripping jaws are individually adjustable in the vertical direction with respect to the said bearing surface.

An embodiment of the object of the invention is illustrated, by way of example, in the accompanying drawing, in which:

Figure 1 is a longitudinal section of the insertion vise in its state of use;

Figure 2 is a plan view of this insertion vise, 15 and

Figure 3 is a cross section according to the line III—III in Figure 2.

The range reducing or auxiliary insertion vise shown in the Figures 1, 2 and 3 has a rectangular supporting plate *a* which is provided with a longitudinal, rectangular opening *a*¹. The plate *a* carries, on its lower side, two guiding bars *b* extending along the longitudinal edges of the opening *a*¹ and forming, together with the plate *a*, guides for a sliding jaw holder *c*¹ which is urged by a tension spring *g*, this jaw holder cooperating with a stationary jaw holder *c*² which is situated at the corresponding end of the opening *a*¹.

Both of the jaw holders *c*¹, *c*² are provided on their opposite sides with dove-tail guides in each of which is slidably fitted a gripping jaw *d*. Each of the jaw holders *c*¹, *c*² carries an adjusting screw *e* screwed therein from below, these screws *e* having a peripheral groove into which engages a bent fork portion *d*¹ of the gripping jaw *d*. Thus, each of the gripping jaws *d* can be adjusted individually in the vertical direction with respect to the bearing surface formed by the supporting plate. This arrangement has also the advantage, that by screwing out the adjusting screws *e* the gripping jaws *d* can be exchanged.

Figure 1 shows the insertion vise in its state of use. On this figure, it can be seen how the insertion vise is applied to a standard vise *s*, which, owing to its size, would not be fit for the working of work-piece *w*. Owing thereto, the work-piece is laid on the supporting plate *a* and is clamped between the vertically adjustable gripping jaws *d* of the insertion vise by closing the standard vise *s*. By operating as just said, the insertion vise is so inserted in the standard vise *s*, that the stationary jaw holder *c*² is turned toward the operator executing the work in order to allow him to have the work-piece as near as possible to him.

What I claim is:

1. A range reducing insertion vise having a supporting plate forming a bearing surface for the workpiece and being provided with a longitudinally extending slot which is of less width 60

than the width of the work-piece, two gripping jaws for holding the latter arranged in said supporting plate and extending through said slot, said gripping jaws being relatively movable rectilinearly toward and away from each other, and means for separately and individually adjusting each of said gripping jaws in the vertical direction with respect to said bearing surface whereby to adapt the gripping surface of each to the adjacent surface of the work-piece to be gripped.

2. A range reducing insertion vise according to claim 1, said gripping jaws being separately and individually removable from said supporting plate, whereby the jaws may be replaced or exchanged.

3. A range reducing insertion vise having a supporting plate forming a bearing surface for the work-piece and being provided with a longitudinally extending slot which is of less width than the width of the work-piece, two jaw holders relatively movable rectilinearly toward and away from each other arranged in said supporting plate and extending through said slot, each of said jaw holders carrying a gripping jaw for holding the work-piece therebetween, whereby said gripping jaws are also relatively movable rectilinearly toward and away from each other, and means for separately and individually adjusting each of said gripping jaws in the vertical direction with respect to its jaw holder and said bearing surface whereby to adapt the gripping surface of each to the adjacent surface of the work-piece to be gripped, said gripping jaws being separately and individually removable from said holders, whereby the jaws may be replaced or exchanged.

4. A range reducing insertion vise having a supporting plate forming a bearing surface for the work-piece and being provided with a longitudinally extending slot which is of less width than the width of the work-piece, two jaw holders arranged in said supporting plate, one of said holders being fixed at one end of said slot and the other being slidably rectilinearly toward and away from said fixed holder, said jaw holders being severally provided on their interior opposing surfaces with a dove-tail guide, a gripping jaw mounted on each holder and having a dove-tail projection arranged in said guide, whereby said gripping jaws are relatively movable rectilinearly toward and away from each other, and means for separately and individually adjusting each of said gripping jaws in the vertical direction with respect to its jaw holder and said bearing surface whereby to adapt the gripping surface of each to the adjacent surface of the work-piece to be gripped, said gripping jaws being separately and individually removable from said holders, whereby the jaws may be replaced or exchanged.

WALTER HAAS.
